(57) **CLAIM**

The ornamental design for a watch bracelet, as shown and described.

DESCRIPTION

FIG. 1 is a perspective view of a watch bracelet showing my new design;

FIG. 2 is a top plan view thereof;

FIG. 3 is a right side elevational view thereof;

FIG. 4 is a front elevational view thereof; and,

FIG. 5 is a bottom plan view thereof.

The left side elevational view is a mirror image of the right side elevational view; the rear elevational view is a mirror image of the front elevational view.

The broken lines shown in the drawings represent unclaimed portions of the design and form no part thereof.
